Attorney

UNITED STATES PATENT OFFICE.

JACOB J. FRIEND, OF EVERETT, MASSACHUSETTS.

CASTER.

1,383,396.

Specification of Letters Patent.

Patented July 5, 1921.

Application filed October 19, 1920. Serial No. 418,077.

To all whom it may concern:

Be it known that I, JACOB J. FRIEND, a citizen of the United States, residing at Everett, in the county of Middlesex and State 5 of Massachusetts, have invented certain new and useful Improvements in Casters, of which the following is a specification, reference being had to the accompanying drawings.

10 This invention relates to certain improvements in casters, and it is an object of the invention to provide a novel and improved device of this general character especially designed and adapted for use in connection 15 with articles of furniture or the like of pronounced weight.

It is also an object of the invention to provide a novel and improved caster of this general character including a plurality of balls 20 associated with a mounting therefor adapted to be detachably engaged with the body or main portion of the caster proper.

An additional object of the invention is to provide a novel and improved device of this 25 general character embodying an assembly including a plurality of balls and a mounting therefor, said mounting being operatively engaged with a cup or bowl adapted to contain a suitable compound or solution repugnant to insect life.

The invention consists in the details of construction and in the combination and arrangement of the several parts of my improved caster whereby certain important advantages are attained and the device rendered simpler, less expensive and otherwise 35 more convenient and advantageous for use, as will be hereinafter more fully set forth.

The novel features of my invention will 40 hereinafter be definitely claimed.

In order that my invention may be the better understood, I will now proceed to describe the same with reference to the accompanying drawings, wherein:

45 Figure 1 is a view partly in side elevation and partly in section illustrating a caster constructed in accordance with an embodiment of my invention.

Fig. 2 is a view in bottom plan of the structure as illustrated in Fig. 1.

Fig. 3 is a sectional view taken substantially on the line 3—3 of Fig. 1, and

Fig. 4 is an enlarged fragmentary view

illustrating in detail a portion of the connecting means between the mounting for the 55 balls and the bowl or body portion of the caster.

As disclosed in the accompanying drawings, S denotes a shank or stem adapted to be inserted in a conventional manner in a 60 socket carried by an article of furniture or the like. In the present embodiment of my invention, this shank or stem S is tubular or 65 hollow with its outer end closed and with its opposite end portion defined by an outstanding flange 1 adapted to be spot welded or otherwise secured to the bottom wall 2 of the cup or bowl C. The cup or bowl C, together with the stem or shank S, constitutes the main or body portion of the caster.

Disposed through the bottom wall 2 of the cup or bowl C adjacent the periphery thereof and preferably equidistantly spaced circumferentially of said bottom wall 2 are the headed members or rivets 3, the same being 75 herein disclosed as three in number. Each of the members or rivets 3 depends below the bottom wall 2 of the cup or bowl C and is provided with the head 4.

5 denotes a plate preferably circular in 80 form and which has its marginal portion defined by an upstanding flange 6. The upper or free edge of the flange 6 is defined by an inwardly directed annular flange 7 provided in its free marginal portion with the 85 notches or recesses 8. The notches or recesses 8 are of such size to readily permit the passage of the heads 4 beyond the flange 7 when the plate 5 is to be operatively engaged with the bottom wall 2 of the cup or bowl C. 90 After this initial operation, the plate 5 is slightly rotated, resulting in the head 4 of each of the members or shanks 3 passing below or underlying the flange 7, whereby the plate 5 is effectively anchored to the cup or 95 bowl C. By this arrangement, it will be readily seen that the plate 5 may be conveniently applied or removed as the occasions of practice may require.

To one side of one of the recesses or 100 notches 8, the free marginal portion of the flange 7 has pressed therefrom a slight protuberance or bulge 9 beyond which the head 4 of the adjacent member or rivet 3 is adapted to be forced. By this means, it will be 105 readily understood that the protuberance or

bulge 9 provides an effective means to prevent retrograde rotation of the plate 5 and thereby serves to eliminate the possibility of said plate 5 becoming accidentally disengaged from the cup or bowl C.

The flange 7 is also provided in its free marginal portion at a desired point between the remaining two notches or recesses 8 with a second protuberance or bulge 9' pressed therefrom. This second protuberance or bulge serves to limit the extent of initial rotation of the plate 5 when the same is operatively engaged with the cup or bowl C and is of particular advantage in preventing such continued movement when the caster is in applied position so that by the use of this second protuberance or bulge 9' in connection with the first named protuberance or bulge 8, the plate 5 is positively maintained against accidental displacement from working position.

The plate 5 is provided with a plurality of circumferentially spaced openings 10 preferably three in number and through each of which partially extends from above a ball B of glass or other suitable material and which is adapted to have contact with a floor or other supporting surface. The plate 5 between each pair of adjacent openings 10 is also provided with smaller openings 11 through which dirt or other foreign matter accumulating within the housing afforded by the plate 5 and its flange 6 may readily escape.

It is also to be particularly noted in Fig. 4 that one side portion of the wall defining a notch 8 has its under surface rounded, as at 12, to facilitate the requisite passage of the head 4 of the member or rivet 3 along the adjacent portion of the flange 7.

A denotes an annular member removably engaged within the upper portion of the cup or bowl C and this member embodies an inwardly and downwardly curved plate 14 overlying the peripheral marginal portion of the cup or bowl C. The outer marginal portion of the plate 14 is provided with an inwardly directed flange 15 which snugly engages within the top portion of the cup or bowl C and has frictional contact therewith so that the member A is effectively maintained in applied position. This annular member A serves to prevent splashing of the poisonous compound or solution arranged within the cup or bowl C outwardly from said cup or bowl and particularly during the periods when the furniture or the like to which the caster is applied is being moved from one location to another.

From the foregoing description it is thought to be obvious that a caster constructed in accordance with my invention is particularly well adapted for use by reason of the convenience and facility with which

it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. A caster comprising a body member, a plate underlying the body member and provided with a flange disposed toward the body member, coacting means carried by the flange and body member whereby the same may be detachably engaged one with the other, and a ball partially disposed through the plate.

2. A caster comprising a body member, a plate underlying the body member, coacting means carried by the plate and body member whereby the same may be detachably engaged one with the other upon relative rotation of said body member and plate, and a ball partially disposed through the plate.

3. A caster comprising a body member, a plate underlying the body member, coacting means carried by the plate and body member whereby the same may be detachably engaged one with the other upon relative rotation of said body member and plate, and a ball partially disposed through the plate, said body and plate being provided with coacting means for normally holding the same against relative rotation.

4. A caster comprising a body member, a plate underlying the body member and provided with a flange disposed toward the body member, coacting means carried by the flange and body member whereby the same may be detachably engaged one with the other, and a ball partially disposed through the plate, said flange of the plate being provided with means to hold the same against accidental disengagement from the body member.

5. A caster comprising a body member, a plate underlying said body member and provided with a flange disposed toward the body member, headed members depending from the body member, the free marginal portion of the flange of the plate being provided with an inwardly directed flange having notches through which the headed members are adapted to extend, said headed members underlying the second named flange upon partial rotation of the plate, and a ball partially extending through the plate.

6. A caster comprising a body member, a plate underlying said body member and provided with a flange disposed through the body member, headed members depending from the body member, the free marginal

portion of the flange of the plate being provided with an inwardly directed flange having notches through which the headed members are adapted to extend, said headed members underlying the second named flange upon partial rotation of the plate, a ball partially extending through the plate, and means carried by the second named flange and coacting with certain of the headed members for limiting the rotary movement 10 of the plate.

In testimony whereof I hereunto affix my signature.

JACOB J. FRIEND.
